UNITED STATES PATENT OFFICE

2,158,856

MERCURY BOILER

William L. R. Emmet, Schenectady, N. Y., assignor to General Electric Company, a corporation of New York

Application May 17, 1935, Serial No. 22,119

9 Claims. (Cl. 122—235)

The present application is a continuation in part of my application Serial No. 691,133, filed September 27, 1933. The invention relates to mercury boilers and has for its general object the provision of an improved construction and arrangement of mercury boilers in which a comparatively small amount of mercury liquid is necessary to operate the boiler and in which the liquid may be heated to high temperature without endangering the heating elements for conducting the fluid through the combustion chamber or chambers of the boiler.

The problems met with in the use of mercury in boilers are radically different from those appearing in the design of steam boilers. These differences are partly due to the different physical characteristics of mercury and water and partly due to the high cost of the first. Mercury has high density, high surface tension, low specific and latent heat, and little tendency to wet steel or iron surfaces.

The different characteristics between mercury and water lead to different boiler designs and it is important to note that certain apparent similarities and equivalents of the two kinds of boilers are actually fundamentally different because such "seeming equivalents" are provided and suggested for different reasons, or from another view-point, serve different purposes in the two cases. After an extensive study of the mercury boiler design, I have found that better results, better economy and efficiency are obtained with comparatively small boilers or heating units than with large ones. Therefore, in accordance with my invention, I sub-divide a large boiler into a plurality of smaller units having independent sources of heat and arrange them so that they may be operated individually or collectively. Each unit comprises a plurality of tubes having upper ends connected to a drum and being arranged to form a substantially cylindrical combustion chamber. The source of heat supply is preferably provided near the lower part of the chamber. The products of combustion then pass upward through the chamber and thereby deliver the heat energy through the tubes to the mercury therein. Since the temperature range in which heat is delivered to the mercury is high compared with that in steam boilers, and since the rate of radiation varies with the fourth power of the absolute temperature, a relatively large proportion of the heat energy produced in the combustion chamber can be delivered by radiation. In my improved boiler arrangement, extreme application is made of this feature in that at least 75 per cent of the

heat energy is delivered in the form of radiant heat to the tube elements. To make this possible, the height of the combustion chamber is made at least twice that of its maximum diameter so that the mercury liquid which is supplied to the lower ends of the tubes reaches its boiling temperature and is vaporized in the upper portions only of the tubes. This is important because liquid mercury contained in the lower tube portions permits a much higher heat transfer than were a mixture of liquid and vapor contained in these lower portions. From another angle, I provide a boiler in which the vaporization zone is shifted to a high level in the combustion chamber. In such an arrangement with the source of heat supply in the lower end of the combustion chamber, a very high heat transfer takes place through the lower tube portions, and the transfer of heat decreases toward the upper ends of the tubes. This decrease of heat transfer however does not endanger the upper tube portions by excessive rise in temperatures because the radiation towards said portions is much less than towards the lower portions.

For a better understanding of the above and other features of my invention, attention is directed to the following description and the claims appended thereto in connection with the accompanying drawings.

In the drawings, Fig. 1 represents a sectional front view of a boiler embodying my invention; Fig. 2 is a sectional top view of a boiler arrangement; Figs. 3 and 4 illustrate to an enlarged scale certain parts of Fig. 1; Fig. 5 is a diagrammatic illustration of a boiler embodying my invention; Fig. 6 is a sectional view of a modification embodying my invention; and Figs. 7 and 8 are detail view of Fig. 6; Fig. 9 is a sectional view of another modification of my invention; and Figs. 10 and 11 are perspective detail views of Fig. 9.

The boiler comprises a plurality of heating units 10 and 11 (Fig. 2) arranged in a chamber or furnace having a wall 15 and a partition 16 separating the units 10 and 11 to define two groups. Each unit includes a preheater 17 connected by a conduit 18 to a liquid supply header 19 (Fig. 5) and by a conduit 20 to the boiler proper 21. Each boiler proper or unit has a vapor discharge conduit 22 connected to a vapor header 23 (Fig. 5). Provided in the liquid supply header and in the vapor discharge header are valves 24 and 25 respectively for disconnecting the individual units to operate the power plant with varying numbers of units in accordance with the load demand. This permits the operation of a power plant at maximum efficiency.

Referring now to Fig. 1 where I have shown more in detail the arrangement of a heating unit, together with a preheater for the unit, the unit comprises an outer cylindrical or tubular wall 26 made of fireproof material. The term cylindrical is used in a broad meaning and not limited to a structure having an annular or circular cross-section. A plurality of tubes 27 are vertically arranged to line the interior of the wall 26 and held in position by means of hoops or rings 28 embedded in the wall. Each tube is fastened to the rings by welds 29 (Fig. 4). The spaces defined between adjacent tubes are filled with insulating material 30 and the outer surface of the wall 26 is covered by a metal sheet 31.

In manufacturing the structure above described I preferably weld first the tubes to the hoops 28 and thereafter provide the wall 26 and the metal covering 31. The tubes, together with the outer wall, form a combustion or radiation chamber or space 32. The lower ends of the tubes are connected to an annular header 33 and the upper ends of the tubes are connected to a drum 34 concentrically located above the outer wall 26 of the unit, the upper ends of the tubes being bent inwardly at different angles or degrees and have their ends projecting into substantially uniformly distributed openings in the lower curved portion of the drum 34. The drum is provided with a head 35 held in position by locking means 36 and sealed by a ring 37, more fully described in my Patent 1,902,494, filed September 17, 1928, and assigned to the same assignee as the present application. As pointed out above, the upper ends of the tubes are spaced from each other defining thereby intermittent spaces through which gases formed in the combustion chamber may escape.

A displacement or filler block 38 having openings 39 (Fig. 3) is provided within the lower portion of the drum and held in position by means of stops 40 fastened to the wall of the drum. Each opening 39 of the filler block is in alignment with an opening in the bottom of the drum. A sleeve 41 inserted in the recessed upper end of each tube 27 projects into the opening 39 of the displacement block. A tubular member 42, forming in substance an extension of the tube 27 is fastened to the displacement block by a weld 43 and extends above the liquid level in the drum. Fluid expelled from the tube 27 is conducted through the sleeve 41 into the tubular member 42 whence it is expelled from the upper end thereof. In order to prevent the liquid expelled from the tubes 42 from flowing together with the discharged vapor into the discharge conduit 22, I provide on top of each tubular member 42 a liquid-vapor separating and liquid-reversing device, in the present instance shown as a cap 44, opening in a downward direction and having an edge portion fastened to the end face of the tubular member 42. The opening of cap 44 is considerably wider than the opening of the tubular member 42.

During operation, liquid discharged from the tubular member 42 is directed along the inner surface of the cap and reversed, to be expelled from the cap in a downward direction, as indicated by an arrow 45 (Fig. 3). Vapor discharged from the tubular member 42 does not follow the inner curvature of the cap owing to its lower gravity, but escapes in a sidewise direction from the lower end of the cap opening whence it rises toward the discharge conduit 22 as indicated by an arrow 46. It is important to note that the

tubular member 42 has an inner diameter which is equal or smaller than the inner diameter of the tube 27. This causes the flow of fluid from the tube 27 into the tubular member 42 being discharged at high velocity, resulting in a better separation of liquid from vapor and a better circulation of fluid.

Liquid is conducted from the drum to the lower header by means of conduits or tubes 47 arranged outside the wall 26. These tubes with regard to the downward direction of the flow of fluid therethrough may be termed "down-tubes", whereas the tubes within the combustion chamber 32 may be termed "up-tubes". In the present instance, I have shown four down-tubes 47 having their upper ends connected to a central downwardly projecting portion 49 of the drum. The portion 49 forms an extension of a central bore in the displacement block and defines a manifold to which the down-tubes 47 are connected. In order to obtain uniform flow of liquid from the drum 35 to the lower header 33, the down tubes are symmetrically spaced and have in the present instance their lower ends branched into two branches 50 and 51 connected to the annular header 33. Thus, the four down-tubes have eight branches connected to points of said header 45 angular degrees apart. The upper ends of the down-tubes 47 are covered with lagging 52 to prevent heating of liquid flowing therethrough by the gases escaping from the combustion chamber.

Liquid is conducted to each drum from the preheaters 17 comprising an inlet header 53 receiving liquid from the conduit 13 and an outlet header 54 discharging preheated liquid through the conduit 20 to the drum. The two headers are connected by a plurality of hairpin-shaped tubes 55. The preheater is located in the upper space of a conduction or gas chamber 56 defined between the wall 26 of the boiler proper and a partition or baffle 57. To utilize the heat energy remaining in the gases discharged from the combustion chamber after they have passed the preheater, I may provide in the lower portion of the conduction space another heating means, in the present instance indicated as a steam broiler 58 comprising an inlet header 59 receiving water from any suitable source, not shown, and an outlet header 60 connected to the inlet header 59 by a plurality of tubes 61 and provided with a steam-discharge tube or conduit 62.

Fuel to be burned in the combustion chamber is supplied through a burner 63 provided in a central opening in the bottom of the combustion chamber. Air for maintaining the combustion is conducted to the space around the burner by a conduit 64 connected to an air preheater 65 having an inlet 66 and being located in the lower part of a flue defined by the outer furnace wall 15 and the partition 57.

During operation, liquid is conducted through the preheater 17 to the drum of the boiler proper, whence the liquid flows through the down tubes 47 and the lower header 33 into the up-tubes 27. The liquid is heated and partly evaporated in the up-tubes and expelled into the drum where the vapor is separated from the liquid and discharged through the conduit 22. The liquid expelled from the up-tubes into the drum is recirculated through the down-tubes and the up-tubes. Each liquid particle is circulated many times from the drum through the down- and up-tubes until it is evaporated. The circulation of liquid permits the operation of the boiler or generator at high 75

temperatures without endangering the fluid-conducting elements or up-tubes in the combustion chamber.

The circulation of the fluid in the arrangement just described takes place by gravity; that is, the liquid contained in the down-tubes 47 forces the mixture of liquid and vapor contained in the up-tubes up into the drum. The heating unit is preferably built standard size. This permits the manufacture of an elastic fluid-generating plant with any desirable output by the provision of a suitable number of standard heating units. Another advantage of the arrangement is, as pointed out above, that the heating units 15 may be operated individually and collectively. Thus, in the present arrangement, where the generators comprise six units, three or less units may be operated at one time.

In the arrangement described herein the heating tubes are substantially entirely filled with mercury liquid during starting operation. A small amount of liquid may even be contained in the drum. In order to reduce the time necessary for starting the boiler, it is desirable to remove a portion of the liquid from the heating tubes, that is, to lower the cold liquid level therein as far as possible without endangering the empty tube-portions due to excessive heating during starting. Also, I have found it desirable to filter the mercury liquid conducted to the lower ends of the heating tubes in order to remove undesirable substances such as dirt therefrom. Such substances may cause clogging of the heating tubes as well as the down-tubes conducting mercury to the lower ends of the heating or up-tubes. This is accomplished in accordance with my invention by the modified arrangement shown in Figs. 6 to 8.

This arrangement comprises a plurality of up-tubes or heating tubes 80 having lower portions 81 arranged to form a cylindrical combustion chamber 82 having a height of more than twice its diameter. Intermediate portions 83 of the heating tubes are bent inwardly at various angles and degrees and upper portions 84 forming continuations of the intermediate portions are arranged in parallel relation to form a plurality, in the present instance four rings or rows of tubes substantially uniformly spaced apart. A baffle 85 of heat-resisting material is held between the inner ring or row of tubes to prevent combustion gases from escaping along the cylindrical space defined by this inner ring of tubes or, from another viewpoint, to cause combustion gases to flow through the intermediate spaces defined by the bent or necked-in intermediate and upper portions of the heating tubes. The lower and intermediate portions of the tubes line a refractory wall 86 corresponding to the wall 26 of Fig. 1. The tubes are securely held on this wall by hoops or rings 87 embedded in the wall and welded to the tubes. The outer surface of the wall 86 is covered by sheet lining 88. The tubes when assembled form a bottle-shaped structure with a necked-in portion having an upper end to be connected to a drum or upper header and an open bottom to accommodate a source of heat as will be described hereafter. The lower ends of the tubes are connected to a header 89 which in the present instance is protected from radiant heat by a refractory wall 90. The latter, together with the outer sheet metal 88 form an annular chamber 91 readily accessible to permit repair at the lower ends of the tubes and also if necessary cleaning of the header 89. Fuel and air are conducted to the lower end of the combustion chamber by

means including a burner 92 and an air conduit 93 corresponding to elements 63 and 64 respectively of Fig. 1. All of the mercury heating tubes are exposed to radiant heat and the major portion, preferably at least 75% of the total heat produced in the combustion chamber is transmitted to the tubes in the form of radiation. The upper ends of the heating tubes are connected to a drum 94 having an axis in alignment with that of the combustion chamber. As stated before, these upper ends of the heating tubes are uniformly spaced apart and, as shown in the drawings, they are inserted in uniformly spaced openings extending substantially over the entire area of the bottom wall of the drum 94.

Fluid, that is, mixture of mercury liquid and vapor, is discharged from the upper ends of the heating tubes into the drum through the intermediary of liquid vapor separating means. These means include a nozzle member 95 for each tube end. The nozzles 95 are fastened to the tube ends and extend into the lower ends of ducts formed by a plurality of tubes 96 held on a perforated plate 97. The plate 97 is secured to the drum by bolts 98. The nozzles 95 are disposed below the normal liquid level in the drum and the upper ends of the tubes 96 extend above the normal liquid level. The upper ends 99 of the tubes 96, as can best be seen in Fig. 7, are curved and arranged to discharge fluid laterally in a somewhat tangential direction towards the cylindrical inner surface 100 of the drum 94. The inner row of tubes 96 is higher than the outer rows. In the present instance the ends of the four rows of tubes 96 are disposed on a conical surface and the discharge ends 99 of these tubes are arranged so that the streams discharged therefrom do not interfere with each other, each end 99 discharging a stream directly towards the wall surface 100. This arrangement results in an ejector action at the top of the nozzles and causes mercury surrounding the nozzles 95 to be picked up by the discharging stream of liquid and vapor. This action results in a relatively low velocity discharge of liquid in the form of large drops or clots in contrast to a finely divided high velocity spray occurring without the ejector action. The plate 97 as shown is spaced somewhat from the adjacent surface of the bottom wall so that mercury may freely flow to the ends of the nozzles 95, causing an ample supply of liquid to the discharge ends of the nozzles 95, which liquid is picked up by the streams discharged from said nozzles. By this arrangement the discharge of finely divided mercury liquid is eliminated. This is an important feature of my arrangement. Extensive experiments have shown that the discharge of liquid in the form of a finely divided spray is undesirable because such fine particles are apt to be picked up by the vapor and discharged by the boiler to turbines or other parts to which vapor is conducted. The carrying-over or discharge of liquid even in very small quantities is highly objectionable not only because the presence of liquid in the vapor impairs the efficiency of a turbine or other apparatus to which the vapor is conducted, but also because it tends to hasten the loss of certain alloys associated with the mercury in present day mercury boilers. Such alloys, like sodium or aluminum, are mixed with the mercury to increase the rate of heat transfer to the boiler heating elements and also to reduce the dissolving of iron or like metal from which the boiler walls are made by the action of mercury in contact therewith. In view of these facts the complete

absence of priming or carrying-over of liquid becomes more important in a mercury boiler than in boilers using water or other liquid as operating substance.

Whereas the head 35 of Fig. 1 is secured to the drum by means described in my aforementioned Patent No. 1,902,494, I provide in the modification of Fig. 6 another improved arrangement for securing a head to a drum. As shown in Fig. 6, the upper part of the inner surface 103 of the drum 95 is recessed to form a shoulder 101. The upper end of the drum has an elliptical-shaped opening 102. An elliptical head 103 with a shoulder 104 engages the shoulder 101 formed on the recessed inner wall of the drum. During assembly the elliptical head 103 is put into the elliptical opening of the drum and after it is inserted it is turned through ninety angular degrees.

Fig. 7 shows the elliptical head in its relative position to the elliptical drum opening during assembly. As will be readily understood, the height of the recessed portion of the inner surface must be sufficient to permit insertion and assembly of the elliptical head. The head is held in position and forced towards the shouldered portion of the wall 94 by means including studs 105 secured to the head, and connected to a plate 106 by means of nuts 107. The plate 106 engages the upper face or edge of the drum so that tightening of the nuts 107 causes the head to be forced into close engagement with the shoulder 101 on the drum 94. The bolts 105, as shown in the drawings, are preferably spaced from the edge of the top plate 106 so that the springing action of the top plate will maintain a constant upward pressure on the engagement joint between the head and the drum even when there is no pressure or a negative pressure in the drum. The top plate 106 and the head 103 form a space or chamber 108. This space is preferably maintained under a negative pressure, that is, a pressure below atmosphere. This may be accomplished by means including a conduit 109 for connecting the space or chamber 108 to a boiler draft. With this arrangement all leakage of mercury is drained into the suction space 108 and can be condensed and saved. In certain instances it is desirable to maintain within the space 108 an atmosphere of inert or deoxidizing gas such as hydrogen. In the present instance I have shown a pipe 110 for conducting a deoxidizing agent to the suction chamber 108.

Mercury vapor is discharged from the drum by a discharge conduit 111 connected to the upper end of the vapor space. The discharge of liquid mercury particles is further reduced by the provision of a plate 112 having a bent edge secured to the inner surface of the drum by bolts 113 and a central opening 114 forming a path for the mercury vapor to be discharged. As stated before, I provide means for reducing the mercury liquid level during starting or, from another viewpoint, maintaining the mercury liquid at a low level when cold and means for filtering the mercury liquid before it is conducted to the lower ends of the heating tubes. These means include an auxiliary drum 115 disposed external the combustion space and having a bottom 116 located at a level substantially below the desired cold liquid level in the heating tubes. The drum has a cylindrical wall 117. A recessed head portion 119 having an elliptical opening 119 is secured to the upper end of the wall 117 by a weld 120. The elliptical opening of the auxiliary drum is closed by means including a header 121 and a top plate 122 ar-

ranged in similar manner as the head 103 and the top plate 106 of the main drum 94. A negative pressure is maintained within the space defined between the head 121 and the top plate 122 by means including a suction conduit 123 communicating with said space. The auxiliary drum receives mercury liquid from the main drum 94 through a conduit 124. Mercury liquid may be conducted to the auxiliary drum from another source, for instance, a mercury condenser in the case of a power plant through means including a conduit 125 connected to the conduit 124. Mercury liquid is discharged from the auxiliary drum through a conduit 126 connected at its upper end to the bottom of the auxiliary drum and at its lower end to the header 89 by a connecting box 127. A retaining member 128 in the form of a baffle, a screen or the like, is disposed in the lower portion of the auxiliary drum for retaining large pieces of solid material within the auxiliary drum or, from another viewpoint, for preventing large pieces of solid material from entering and clogging the down-tube 126. The retaining or filtering member 128 is secured to a rod 129 extending into the upper portion of the drum and having an arm 130 secured to the wall 117 by bolts 131. With this arrangement the retaining member 128 and solid material collecting thereon may be easily removed from the auxiliary drum after disassembly of the head 121. If desired, the auxiliary drum may be used also as a means for feeding certain ingredients, such as aluminum, sodium or the like, to the boiler. Such ingredient when supplied in the form of solid rods or pieces dissolves gradually within the auxiliary drum, whence it is carried into the heating tubes of the boiler. When cold, the boiler is filled with mercury 132 to a level indicated by the dash-dotted line 133. The level 133, as shown in the drawings, is below the upper end of the combustion chamber. Thus, the portion of the heating tubes disposed above the level is empty during starting operation. This permits quick starting due to the relatively small static head acting on the mercury within the lower ends of the heating tubes. During starting the mercury due to expansion rises within the heating tubes to a level above that of the plate 97 in the main drum, whence the liquid is discharged through the conduit 124 to the auxiliary drum to be recirculated through the heating tubes. As pointed out before, the velocity of the mixture discharged from the upper ends of the heating tubes through the nozzles 95 is considerably reduced due to the fact that said nozzles are normally immersed in mercury liquid. The streams of the mixture are discharged laterally from the upper ends of the tubes 96 towards the inner surface 103 of the drum whereby the liquid content of the mixture having high inertia is forced outward towards the surface 100 and the vapor content of the mixture having less inertia escapes towards the center of the drum through the opening 114 to the discharge conduit 111.

The arrangement shown in Fig. 9 comprises a drum 140 covered with lagging 141. The drum 140 has a bottom 142 with a reinforced or heavier central portion 143. A cylindrical wall 144 is secured to the bottom portion 142 by an annular weld 145. A plurality of annular rows of heating tubes 146 is connected to the bottom. The tubes project through openings in the bottom and have their upper ends united with the adjacent bottom portions by fused metal 147. The arrangement of the lower portions of the heating tubes and the combustion chamber may be the

same as that described above with respect to Figs. 1 to 8.

The boiler of Fig. 9 includes an improved arrangement for securing and sealing a head to the drum. In accordance with my invention, an annular head 148 is screwed into a threaded portion 149 of the cylindrical wall 144. The drum and its head are of comparatively light construction. For this reason the head 148 is directly fastened to a central bottom portion 143 by means of a bolt 150 secured to the portion 143 and projecting through a central opening in the head 148. The central portion of the head 148 is forced inward, that is, in the direction towards the bottom by means of a nut 151 on the outer end of the bolt. Thus, the provision of the bolt permits safe operation at high pressure with a comparatively light drum structure. In order to prevent leakage of fluid along the threaded portion of the head and along the bolt, means are provided to completely seal the head to the drum and also to prevent leakage along the bolt. The means for sealing the head to the cylindrical wall 144 comprise a ring 152 secured to the outer surface of the head 148 by a weld 153 and another ring 154 welded to the upper face of the cylindrical wall 144. In the present instance the outer portion of the ring 152 overlaps somewhat the threaded portion of the wall. A cylindrical sheet 155 is secured to the outer edge of the ring 152 by means of a weld 156, and another cylindrical sheet 157 surrounding the sheet 155 is secured to the ring 154 by means of a weld 158. The upper ends or edges of the sheets 155 and 157 are united, in the present instance by a weld 159. Thus, the two sheets form a narrow, annular space receiving all the leakage of fluid passing along the threaded portions of the head and the cylindrical wall and preventing any leakage to the atmosphere.

During manufacture, the inner ring 152 and the sheet 155 are secured to the head 148 after the latter has been fastened to the wall 144. Thereafter the outer ring 154 and the cylindrical sheet 157 are secured to the cylindrical wall 144. Finally, the upper edges of the two cylindrical sheets are united.

As the pressure in the space or chamber defined between the two cylindrical sheets may assume high values during operation, means are provided to prevent bursting of these sheets or, from another viewpoint, to limit the radial distance between the cylindrical sheets. This means in accordance with my invention comprises two rings, an inner cylinder or ring 160 placed on top of the inner ring 152 and closely spaced with the cylindrical sheet 155, and an outer cylinder or ring 161 placed on top of the outer ring 154 and surrounding in closely spaced relation the outer cylindrical sheet 157. Thus, the two cylinders or rings 160 and 161 are loosely placed on top of the rings 152 and 154 respectively to form an annular space for accommodating the cylindrical sheets 155 and 157 and preventing bursting of these sheets during operation.

The arrangement for sealing the upper end of the bolt to the head 148 is similar to the one just described. The upper end of the bolt and the nut are surrounded by a wall 162 secured to the head 148 by a weld 16. A head 164 is screwed into an upper portion of the wall 162. The wall 162 and the head 164 define a chamber 165 for receiving leakage passing along the bolt 150. The means for preventing leakage from this chamber to the atmosphere include a ring 166 with a cylindrical sheet 167 secured to the head 164 and a ring 168 with a cylindrical sheet 169 surrounding the cylindrical sheet 167 and secured to the wall 162. From another viewpoint, the rings 166 and 168 may be considered reinforced flanges of the cylindrical sheets 167 and 169 respectively. The upper ends of the sheets are united by a weld 170. The two sheets form a narrow space for receiving leakage passing along the threaded portion of the wall 162. The two cylinders or rings 171 and 172 placed on top of the rings 166 and 168 respectively form an annular space 173 for accommodating the cylindrical sheets and for limiting the expansion of the sheets, that is, of the space defined between them.

The sealing arrangement above described is simple in design and may be manufactured at low cost. An upper portion of the drum, forming a vapor space is connected to a vapor discharge conduit 174 and a lower portion of the drum normally filled with liquid is connected to a liquid discharge conduit or down-tube 175.

Another important feature of the construction shown in Fig. 9 is an improved arrangement for discharging a mixture of mercury and vapor from the tubes into the drum and for separating this mixture to prevent discharge of liquid through the vapor discharge conduit 174. This means comprises a lower cage 176 and an upper cage 177. The lower cage 176 has an outer cylindrical wall 178 closely spaced with the inner surface of the drum, an inner cylindrical wall 179 closely spaced with the central bottom portion 143 and an intermediate cylindrical wall 180. Deflectors or baffles 181 are fastened to these walls and arranged so that adjacent baffles 181 together with adjacent portions of the walls or rings form a discharge channel 182 for receiving the mixture discharged from the upper ends of two radially spaced tubes, an outer tube 183 and an inner tube 184. The space defined by adjacent baffles is normally filled with mercury liquid so that the velocity of the mixture discharged by the heating tubes is considerably reduced and the mercury liquid retained, that is, substantially prevented from passing into the vapor space of the drum. The arrangement of the baffles is such that vapor and some liquid discharged from the upper end thereof assumes a somewhat circular path substantially concentric with the inner surface of the drum.

The lower cage 176 is secured to the wall of the drum by bolts 185. In a preferred embodiment the upper portions of the baffles 181 are inclined at an angle of about thirty degrees (Fig. 11) to the horizontal. The upper cage 177 (Fig. 10) serves to separate liquid particles entrained in the vapor discharged from the lower cage 176. The upper cage comprises an outer row or ring of baffles 186 and an inner ring or row of baffles 187 arranged in staggered relation with respect to the outer baffles or deflectors. The two rows of baffles are connected and held together by means of three concentrically spaced rings 188, 189 and 190. The outer ring 190 is provided with lugs 191 secured to the inner surface of the wall 144 by means of screws 192. The inner ring 188 is held in concentric relation in the drum by means including a sleeve 193 surrounding the bolt 150 and webs 194 connecting the sleeve with the inner ring 188. The lower end of the sleeve 193 rests on the central bottom portion 143 (Fig. 9). In a preferred embodiment the lower portions of the baffles 186 and 187 are inclined towards the horizontal at an angle of about thirty degrees.

The lower cage 176 is secured to the wall of the drum by bolts 185. In a preferred embodiment the upper portions of the baffles 181 are inclined at an angle of about thirty degrees (Fig. 11) to the horizontal.

The upper cage 177 (Fig. 10) serves to separate liquid particles entrained in the vapor discharged from the lower cage 176. The upper cage comprises an outer row or ring of baffles 186 and an inner ring or row of baffles 187 arranged in staggered relation with respect to the outer baffles or deflectors. The two rows of baffles are connected and held together by means of three concentrically spaced rings 188, 189 and 190. The outer ring 190 is provided with lugs 191 secured to the inner surface of the wall 144 by means of screws 192. The inner ring 188 is held in concentric relation in the drum by means including a sleeve 193 surrounding the bolt 150 and webs 194 connecting the sleeve with the inner ring 188. The lower end of the sleeve 193 rests on the central bottom portion 143 (Fig. 9). In a preferred embodiment the lower portions of the baffles 186 and 187 are inclined towards the horizontal at an angle of about thirty degrees.

angle of approximately thirty degrees (Fig. 10) but in opposite direction to the inclination of the upper portions of the baffles 181 of the lower cage. With this arrangement, liquid particles discharged from the lower cage are thrown against the lower portions of the baffles 186 and 187 of the upper cage and returned to the liquid space.

During manufacture, the lower and the upper cage after being completely assembled are inserted in the drum and secured to the cylindrical wall 144.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent of the United States is:

1. A mercury boiler including a cylindrically shaped refractory wall, a plurality of vertical tubes lining the wall and forming a cylindrical combustion chamber, the height of the chamber being more than twice its diameter, a cylindrical drum located above the tubes, the drum being in alignment with the cylindrical combustion chamber and having a bottom with uniformly spaced openings over its entire area connected to the tubes, a block in the drum for displacing mercury liquid, the upper ends of the tubes being bent inwardly at varying angles to form intermittent spaces through which gases may escape from the combustion chamber, a source of radiant heat located near the lower portion of the chamber, and conduit means centrally connected to the bottom of the drum for conducting mercury liquid to the lower ends of the tubes, the arrangement being such that at least 75 per cent of the total heat produced is delivered by radiation to all of the mercury liquid filled heating tubes.

2. A mercury boiler including a plurality of heating tubes arranged to assume the shape of a bottle with the lower portions of the tubes forming a cylindrical combustion chamber and the upper portions of the tubes bent inward and uniformly spaced within the entire cross-sectional area of the necked-in portion of the bottle contour, and a cylindrical drum including a displacement block for mercury and a central bottom portion with uniformly spaced-apart openings for receiving the upper ends of the tubes.

3. A mercury boiler including a cylindrically shaped refractory wall, a plurality of substantially vertical heating tubes lining the wall and forming a cylindrical combustion chamber, the height of the chamber being more than twice its diameter, a cylindrical drum with its axis in alignment with that of the combustion chamber being located above and connected to the tubes, the upper ends of the tubes being bent inwardly at varying angles to form intermittent spaces through which gases may escape from the combustion chamber, a source of radiant heat located near the lower portion of the chamber to radiate heat towards the lower portions of all of the heating tubes, an extension for each tube to discharge liquid and vapor in downward direction at points above the liquid level in the drum, and means for conducting mercury liquid from the drum to the lower ends of the heating tubes comprising an auxiliary drum connected between the first named drum and the lower ends of the heating tubes, said auxiliary drum permitting a

reduction of the cold liquid level in the tubes to a point substantially below the upper ends of the tubes whereby the starting period of the boiler is reduced, and a conduit connected to the auxiliary drum for supplying mercury liquid to the boiler.

4. A mercury boiler including a cylindrically shaped refractory wall, a plurality of substantially vertical heating tubes lining the wall and forming a cylindrical combustion chamber, the height of the chamber being more than twice its diameter, a cylindrical drum located above and connected to the tubes, the upper ends of the tubes being bent inwardly at varying angles to form intermittent spaces through which gases may escape from the combustion chamber, a source of radiant heat located near the lower portion of the chamber to radiate heat towards the lower portions of all of the heating tubes, means for conducting mercury liquid from the drum to the lower ends of the heating tubes comprising an auxiliary drum connected between the first named drum and the lower ends of the heating tubes, and means disposed within the auxiliary drum for retaining solid substances there-

5. A mercury boiler including a cylindrically shaped refractory wall, a plurality of heating tubes lining the wall and forming a cylindrical combustion chamber, the height of the chamber being more than twice its diameter, a drum located above and connected to the upper ends of the heating tubes, upper portions of the tubes being bent inwardly at varying angles to form intermittent spaces through which gases may escape from the combustion chamber, a source of radiant heat located near the lower portion of the chamber to radiate heat towards the lower portions of all of the heating tubes, an extension for each tube to discharge liquid and vapor in downward direction at points above the liquid level in the drum, and means for conducting mercury liquid from the drum to the lower ends of the heating tubes comprising an auxiliary drum connected between the first named drum and the lower ends of the heating tubes, said drum acting as a storage tank for mercury to permit starting of the boiler with the heating tubes only partly filled.

6. A mercury boiler comprising a plurality of heating tubes forming a combustion chamber, a header connected to the lower ends of the heating tubes, a drum connected to the upper ends of the heating tubes, the connections between the heating tubes and the drum being arranged to discharge liquid and vapor from the tubes in downward direction at points substantially above the liquid level in the drum, and means for conducting mercury liquid from the drum to the header including an auxiliary drum having a bottom disposed substantially below the cold liquid level in the heating tubes and permitting starting of the boiler at a liquid level in the heating tubes below the upper end of the combustion chamber.

7. A natural circulation type mercury boiler including a plurality of heating tubes having lower portions defining a cylindrical combustion chamber, a cylindrical drum disposed above the combustion chamber and having a substantially uniformly perforated bottom connected to the upper ends of the heating tubes, mercury normally filling the heating tubes and part of the drum, means including a down-tube for feeding mercury liquid from the drum to the lower ends

of the heating tubes, and a source of radiant heat in the lower part of the combustion chamber for heating the lower portions of all of the heating tubes, the difference in gravity between the mercury contained in the down-tube and in the heating tubes during operation causing relatively rapid flow of mercury through the heating tubes, the height of the heating tubes and the liquid mercury contained therein being sufficient to prevent vaporization of mercury liquid in the heating tubes below a predetermined level in the upper part of the combustion chamber at the normal operating pressure of the boiler so that radiant transmission to the heating tubes of at least 75% of the produced heat energy does not effect undue stresses in the heating tubes.

8. A natural circulation type mercury boiler including a plurality of heating tubes having lower portions defining a substantially cylindrical combustion chamber, a substantially cylindrical drum having a vapor outlet in its upper portion being disposed above the combustion chamber and connected to the upper ends of said heating tubes, mercury normally contained in the heating tubes and partially filling said drum, means including a down-tube extending externally of the combustion chamber for feeding mercury liquid from the lower portion of the drum to the lower ends of the heating tubes, and a source of radiant heat in the lower part of the combustion chamber for heating all of said heating tubes, the difference in gravity head between the mercury contained in the down-tubes and in the heating tubes during operation causing relatively rapid flow of mercury through the heating tubes, the height of the heating tubes and the corresponding head of the liquid mercury contained therein being sufficient to produce a pressure

such as to prevent vaporization of mercury liquid in the heating tubes below a level near the upper part of the combustion chamber at the normal operating pressure of the boiler, the major portion of the radiant heat being transmitted through the walls of the heating tubes to portions filled with liquid mercury as distinguished from a mixture of mercury liquid and vapor whereby the radiant heat is efficiently utilized and undue stresses in the tubes due to poor heat transmission are avoided.

9. A mercury boiler comprising a plurality of heating tubes having lower portions arranged to form a combustion chamber, a source of radiant heat in the lower portion of the chamber to transmit at least 75% of the produced heat energy in the form of radiation to all of the liquid-filled lower ends of the heating tubes, a cylindrically shaped drum vertically disposed above the chamber and having a bottom connected to the upper ends of the heating tubes, a vapor discharge conduit connected to an upper portion of the drum, a cage including a plurality of deflecting members forming curved channels and being disposed in the drum for receiving and deflecting a mixture of liquid and vapor discharged from the upper ends of the heating tubes and causing the mixture to flow in a circular path along the wall of the drum, said cage being at least partly immersed in mercury liquid during normal operation of the boiler, and another cage disposed in the vapor space of the drum and including a plurality of deflecting members obstructing the flow of liquid particles in the vapor space to prevent liquid particles entrained in the vapor from being discharged into the vapor discharge conduit.

WILLIAM L. R. EMMET.
